EP 0563820 3/1993

Primary Examiner — Mimosa De(74) *Attorney, Agent, or Firm* — Barnes & Thornburg LLP(57) **CLAIM**

The ornamental design for a chair for an exercise ball, as shown and described.

DESCRIPTION

FIG. 1 is a perspective view of a front, top, and a first side of an ornamental design for a chair holding an exercise ball; FIG. 2 is a front elevational view of the chair of FIG. 1; FIG. 3 is a rear elevational view of the chair of FIG. 1; FIG. 4 is an elevational view of a second side of the chair of FIG. 1; FIG. 5 is an elevational view of the first side of the chair of FIG. 1; FIG. 6 is a top plan view of the chair of FIG. 1; and, FIG. 7 is a bottom elevational view of the chair of FIG. 1. The broken lines in the drawings depict environmental subject matter only and form no part of the claimed design.
